Fig. 1

Fig. 2

Fig. 3

FIG. 1 is a perspective view of a blower head showing my new design.

FIG. 2 is a plan view thereof; and

FIG. 3 is a bottom plan view thereof.

A hand-held flashlight battery casing is shown in broken lines in FIG. 1 for illustrative purposes only and forms no part of the new design.

The top of the blower head which is shown in plan view in FIG. 2 is flat, with no extrusions beyond the surface of the housing.

I claim:

The ornamental design for a blower head, substantially as shown and described.
